UNITED STATES PATENT OFFICE.

ROSWELL A. MOORE, OF WATERBURY, CONNECTICUT.

DESIGN FOR A CLASP.

46,003.

Specification for Design.

Patented June 23, 1914.

Application filed March 24, 1914. Serial No. 827,009. Term of patent 7 years.

To all whom it may concern:

Be it known that I, ROSWELL A. MOORE, a citizen of the United States, residing at Waterbury, New Haven county, Connecticut, have invented a new, original, and ornamental Design for Clasps, of which the following is a specification, reference being had to the accompanying drawing, forming part thereof.

The figure is a perspective view of a clasp showing my new design.

I claim:

The ornamental design for a clasp, as shown.

ROSWELL A. MOORE.

Witnesses:

MABEL E. BENTLEY,
WALTER T. BRONSON.
